CLAIM

The ornamental design for a lower receiver for modular tactical firearms, as shown and described.

DESCRIPTION

FIG. 1 illustrates a perspective, side view of a new design for a lower receiver for modular tactical firearms depicting a modular lower receiver for use with various barreled actions; FIG. 2 illustrates a side view of a new design for a lower receiver for modular tactical firearms depicting a modular lower receiver for use with various barreled actions;

FIG. 3 illustrates a top view of a new design for a lower receiver for modular tactical firearms depicting a modular lower receiver for use with various barreled actions;

FIG. 4 illustrates a side view of a new design for a depicting a modular lower receiver for use with various barreled actions;

FIG. 5 illustrates a bottom view of a new design for a lower receiver for modular tactical firearms depicting a modular lower receiver for use with various barreled actions;

FIG. 6 illustrates left side elevation view of a new design for a lower receiver for modular tactical firearms depicting a modular lower receiver for use with various barreled actions;

FIG. 7 illustrates a right side elevation view of a new design for a lower receiver for modular tactical firearms depicting a modular lower receiver for use with various barreled actions;

FIG. 8 illustrates a perspective, side view of a new design for a lower receiver for modular tactical firearms depicting a modular lower receiver for use with various barreled actions; and,

FIG. 9 illustrates a side view of a new design for a lower receiver for modular tactical firearms depicting a modular lower receiver for use with various barreled actions.

The broken, dashed lines shown in the various figures depicting the invention in condition of use are included for the purpose of illustrating environment and do not form any part of the claimed design.
